(57) **CLAIM**

The ornamental design for the electrical connector, as shown and described.

DESCRIPTION

FIG. 1 is a perspective view of an electrical connector in accordance with the present design;

FIG. 2 is a front elevational view of the electrical connector illustrated in FIG. 1;

FIG. 3 is a rear elevational view of the electrical connector illustrated in FIG. 1;

FIG. 4 is a side elevational view of the electrical connector illustrated in FIG. 1;

FIG. 5 is another side elevational view of the electrical connector illustrated in FIG. 1;

FIG. 6 is a top plan view of the electrical connector illustrated in FIG. 1; and,

FIG. 7 is a bottom plan view of the electrical connector illustrated in FIG. 1.

The broken lines depict portions of the electrical connector that form no part of the claimed design.
